POSITIVE, NON-INTERFERING SIGNALING SYSTEM

Richard M. Hopkins, Rutherford, N. J., assignor
to American District Telegraph Company, New
York, N. Y., a corporation of New Jersey

Application August 17, 1932, Serial No. 629,119

17 Claims. (Cl. 177—361)

This invention relates to electric signal transmission and alarm systems, and to non-interfering systems, and more particularly to systems of this kind wherein substantially simultaneously initiated signals will be automatically successively transmitted, though it is noted that in some of the claims the invention is not limited to electric transmitters.

One object of the invention is to provide an efficient system of this kind in which a large number of transmitting stations may be operated with only two line-loops, one for transmission and one for signal initiation.

Another object of the invention is to provide a system of this kind in which both loops will be fully and separately supervised and controlled for grounds and other line defects by a circuit and control means similar to the McCulloh system. Another object of the invention is to provide a system of this kind having control switches for McCulloh operation similar to those shown in the United States patent application of Richard Hopkins and Herbert M. Laford, Serial No. 539,316, filed May 22nd, 1931.

The inventive features for the accomplishment of these and other objects are shown herein in connection with an improved positive non-interfering successive alarm system which, briefly stated, includes a recording signal receiver, a supervisory trip control and a grounded main current source, and supervised transmitter and trip loops passing through the transmitters and connected to said source for operating the receiver and said control.

Each transmitter includes a pair of trip magnets in the trip loop, an armature adapted to be attracted by either magnet, when sufficiently energized, to release the transmitter. Water-flow-operated detectors or other signal initiating means are connected with the transmitters respectively, and when operated, direct current from the trip loop through one magnet to the ground, thereby to operate the transmitter.

A retarding resistance interposed in the trip-circuit prevents the passage of enough current for action of the trip magnets until the resistance is removed, as by a retarded relay means actuated by said trip circuit after a period longer than water hammer impulses. Also a non-interference means operated by the transmitter circuit during signaling, operates the relay for interposing said resistance to prevent signal-mixing.

In the accompanying drawings,
55 Fig. 1 is a diagram of the system; and

Fig. 2 is a diagram showing the transmitter and detector connections.

The principal features of the invention will first be very briefly indicated, after which the features will be described in detail.

The system as a whole

The system comprises, briefly stated, a recording signal receiver 11, a supervisory trip control 12, and a grounded main current source 14, having its ungrounded terminal connected to supervised transmitter and trip-loops 9 and 6 passing through the transmitters 18a, 18b, 18n for operating the receiver and said control.

Each transmitter includes a pair of trip magnets 20, 20a (Fig. 2) in series in the trip loop 6, and also a grounded signal wheel 21, a normally closed switch 22, 23, 24 in the transmitter loop 9 and normally out of contact with the wheel 21. An armature 34 is adapted to be attracted by either magnet, when sufficiently energized, to release the transmitter.

There is shown, by way of example, a water-flow detector associated with each transmitter, comprising means 47, 48, 51, 52, normally shunting the magnets, and operative for directing current from said loop 9 through one magnet to the ground, thereby to operate the transmitter. There are also means 60, 61, 62, 63 (Fig. 2), to shunt around the magnets and remove the ground after the signal is completed, to permit other transmitters to operate immediately.

Said signal receiver 11 includes McCulloh type control means 88, 88a, 88g, for adjusting the receiver to meet operating conditions for line defects in the transmitter loop 9, and connecting the "in"-leg of the transmitter loop, through conductor 110, to the source during abnormal operation.

The supervisory trip-control includes, in the trip loop 6, an "in"-leg relay 130a comprising a normally attracted armature 136a connected to said source, and normally engaging a normally engaged contact 138a, for controlling a retarding means including a retarding resistance 140 in the trip-circuit, normally preventing strong enough current for the action of the trip magnets, but in time shunted out by the action of a shunting means 142, 153, set in action by retarded means 143, 159, 147, actuated by said trip armature 136a, the retarded means being sufficiently retarded to prevent the shunting out said resistance 140 unless the detector is operated longer than the usual water hammer impulse.

A non-interference means 164, 165, operated

by the transmitter circuit during transmitting, causes the retarded means 143, 159 to interpose said resistance 140 in the trip circuit, to prevent other transmitters from operating at the same time.

A control means 198, 198a, 198g, of the McCulloh type, serves for adjusting the control 12, in accordance with defects in the trip loop and serves when adjusted to abnormal operation, to 10 open a switch 150, 151, for disconnecting the retarding means 143, 140 from the trip circuit relay, and to connect the "in"-leg terminal 134 of the trip loop 6 through conductors 220, 73 to the ungrounded terminal 16 of the said source 15 for McCulloh operation.

The supervised line loops

This invention is shown in combination with line loop 5, 6, 7, and 8, 9, 10; a receiving station 20 including a receiver 11, 12, and a main current source 14 having grounded and ungrounded terminals 15, 16; said line including any convenient number of transmitters 18a, 18b, 18n and associated transmitter and trip loops 6 and 9 passing 25 through each station, each loop having its legs extending to said station, one leg 5, 8 of each being connected to said main source 14, and the other leg 7, 10 adapted to be grounded or connected to said main source, as will be explained.

The transmitters

Each transmitter 18 includes a series connected pair of trip magnets 20, 20a interposed in the tripper loop 6, a grounded rotary toothed 35 code-signal wheel 21, and a normally closed switch 22, 23, 24, interposed in the transmitter loop 9 and normally out of contact with the wheel 21, and having a pen 24 adapted to be engaged by the teeth of the wheel 21 when rotating, thereby once for each tooth, to ground both legs 8, 10 of the loop 6, and also to break the loop.

The transmitter includes a normally wound clockwork 26, comprising a winding arbor 27 having a squared end, and a clock spring anchored thereto, and a gear train having pawl and ratchet connection with said arbor, thereby to be driven in one direction only by said spring, and comprising a signal wheel shaft 32, carrying said grounded toothed signal wheel 21, and a cam 33. An armature 34, adapted to be raised by either of said magnets when operatively energized, carries a pin 35, forming means for engaging a projection 36 of said clockwork for holding the clockwork against operation when the armature is unattracted, and releasing it when the armature is attracted. A cam 38 on said winding arbor has a notch 39 therein and an extended land portion 40, and is adapted to engage a connecting bar 41 secured to said armature and normally engaged in said notch 39 when the armature is retracted, and engaged by said land portion when the arbor is unwinding to hold the armature in attracted transmitter-releasing position, to prevent the transmitter from stopping until the signal is completed.

Signal initiating means

Signal initiating means such as a water flow detector 43, 44 for a pipe 45 includes a pivoted member 43, 44, carrying a fan 44, and having an outwardly projecting arm 43, carrying an insulator block 45', operating a normally closed shunt switch 47, 48 connected by conductors 49, 75 in shunt around said pair of tripper magnets

20, 20a, and a normally open ground switch 51, 52 adapted when the detector is operated to connect a ground 53, through conductors 54, 55, and switch members 62, 63, with the loop portion 56 between said magnets 20, 20a, whereby said detector 43, 44 operates to open the shunt switch 47, 48, and to connect said portion 56 to the ground 53, the portion of the trip circuit most remote from the source 14 is shunted out, and current passes from said source through one magnet 20, or 20a, to the ground, and if of sufficient strength, attracts the armature 34 and allows the transmitter to send a code-signal to the receiver 11.

Loop restorer

A switch assembly 60, 61, 62, 63 on said transmitter includes a normally open shunt switch 60, 61, shunted around said magnets 20, 20a, and a normally closed switch 62, 63 in series with said ground switch 51, 52, members 60, 63 being 20 connected by an insulating piece 44'. Said cam has a notch 64 normally to receive the pen-end 65 of member 60, and a raised portion 66 adapted to engage said pen after the signal has been initiated and completed, thereby to close the 25 switch 61, 62, thereby shunting around the magnets 20, 20a, and to open the switch 62, 63, thereby removing the ground to allow the passage of current through loop 6 for the operation of other transmitters.

Parts 67, 68 and 69 of Fig. 2 symbolize stop means for the winding arbor and cam 38. When the transmitter runs down the stop projection 68 engages the stop pin 69 and stops the transmitter with the armature raised and the notch 35 64 about the position of the dotted lines. When the arbor is rewound, the projection 68 strikes and stops against the pin 67, with the notch 39 not registering with the bar 41, whereby the projection 35 is held raised until the transmitter 40 runs down enough to bring the notch 64 to the position of the dotted lines and the recess 39 under the bar to lower the projection 35 and stop the transmitter in the position shown.

The code signal recording receiver

The receiving and supervising station 11, 12 includes a code-signal receiver 11 for said transmitter loop 8, 9, 10. The receiver 11 comprises an "out" relay 70 and an "in" relay 70a respectively including magnets 71, 71a between and in series with which the transmitter loop 8, 9, 10 is connected, the magnets 71 being connected by conductor 73 to the terminal 16 of the main source of current, the other terminal 72 of the in-magnets being normally grounded, as will be explained, whereby the circuit is closed and supervised, and being at other times connected to said ungrounded source terminal 16.

The respective transmitter relays 70, 70a comprise also normally attracted armatures 76, 76a, carrying or constituting a movable switch element connected by conductors 77, 73 with the source 14, and respectively engageable with normally engaged contacts 78, 78a, normally constantly engaged by said elements during normally closed circuit, when no signal is being sent, and intermittently engaged during signal sending during open circuit operation in the adjacent leg 8 or 10 of the loop. The relays also 70 respectively include normally constantly disengaged contacts 80, 80a intermittently engaged for signal sending during normal closed circuit operation, and constantly engaged, when no signal is sent, during open circuit condition in the 75

adjacent leg 8 or 10. A pilot lamp 84 and a recorder 85, each having one ungrounded and one grounded terminal, are operated from said relays.

McCulloh-type adjusting means

5 Control means for connecting said lamp and recorder to the proper contacts of said relays to meet operating conditions for defects in the transmitter loop, now to be described, comprises 10 an out-signal switch 88, an in-signal switch 88a, and a ground switch 88g, each switch comprising 15 a substantially semi-circular series or bank of contacts, including a contact N for normal operation, a contact G for grounded closed circuit 20 operation, a contact GO for operation with grounded out-leg of an open circuit, a contact O for open circuit without loop ground, and a contact OG grounded in-leg of an open circuit. A rotatable shaft 89, coaxial with all of said 25 banks, carries insulated contact arms 90, 90a, 90g, for said banks, respectively, the arms being fast on said shaft, and simultaneously engageable respectively with corresponding associated bank contacts, as the shaft is rotated by means 30 of an operating knob 91, fast on said shaft, or in any other suitable manner.

Conductors 93, 94, respectively connect the ungrounded terminals of said recorder and lamp to the contact arms 90, 90a; and a normally open 35 switch 95, 96 connects, by conductors 93, 94, 97, said ungrounded lamp and recorder terminals except when closed during abnormal operation, by a cam 98, 99, fast on said shaft. Said cam is shown with a notch 98 receiving the end of 40 the switch member 95 to allow the switch to open during normal operation, and a land portion 99 for engaging the member 95 and closing the switch when the arms are adapted for abnormal operation, which requires that the recorder be able to operate from both relays.

Conductors 100 connect the normal operation contact N, the grounded closed-circuit operation contact G and the grounded out-leg open circuit contact GO of the out-signal switch 88 with the 45 normally disengaged contact 80, to permit normal signal operation by code signal current through the out-relay when one of said contacts is engaged by the associated contact arm 90, and to permit the supplying to the recorder a current of longer duration should damage to the transmitter loop cause the armature of the out-relay to come to rest on the normally disengaged contact 80, and to cause said pilot lamp to light. This happens when the contact arms are on contacts G or GO, the switch 95, 96 being then closed.

Conductors 101 connect the open circuit contact and the grounded out-leg contacts O and OG of switch 88 to the normally engaged contact 78, whereby when the condition of damage 50 to the line requires the armature to rest on the normally disengaged contact 80, the arm 90 will be engaged with one of said contacts O or OG, and signals to be recorded may be received from the normally engaged contact 78, and current of 55 longer duration caused by change of such line condition, will cause the in-relay armature 76 to rest a longer time on the normally engaged contact to cause the lamp to indicate that the operator should move the contact arm 90 from the engaged bank contact.

Conductors 104 connect the normal operation contact N and contacts G and OG of the in-signal switch 88a with the normally disengaged contact 80a, to transmit code-signal impulses to the recorder when one of such contacts is en-

gaged by the contact arm 90a, and to permit supplying, to the pilot lamp, a current of longer duration to indicate that the arms should be re- 5 volved, should change in the line condition cause the armature to come to rest on the normally disengaged contact 80a.

Conductors 105 connect the open circuit contact GO and the grounded out leg open circuit contact O to the normally engaged contact 78a, whereby when the condition of damage to the line requires the armature to rest on the normally disengaged contact 80a, current for signals to be recorded may be received from the normally engaged contact, and current of longer duration caused by change of such line condition, will 15 cause the pilot lamp to indicate that the contact arm should be moved from such contact.

A conductor 107 connects the terminal 74 of the in-magnet 71a to the contact arm 90g of the ground switch 88g, the latter contact being connected by a conductor 108 to a ground 109, for closed-circuit normal operation of the system; while conductors 110, 73 connect the other ground switch bank contacts G, GO, O and OG to the ungrounded terminal 16 of said source, 20 whereby when abnormal line loop condition requires the current to pass out through the in-magnet, the latter will be connected to the source. 25

Supervisory trip-control

80

The supervisory trip control 12 for said trip loop serves, as will be explained, for controlling the retarding of the tripping impulses in the loop 6, in case of water hammer, and for adjusting the tripper loop in case of line defect, by means 35 similar to the relays 70 and switches 88. Said trip control includes an "out" relay 130 and "in" relay 130a, respectively including magnets 131, 131a between and in series with which the trip loop 5, 6, 7 is connected, the main-source un- 40 grounded terminal 16 being connected by conductors 73, 133 to the out-magnet, the other terminal 134 of the in-magnet being normally grounded, whereby the circuit is normally closed and supervised, and being at other times connected to said ungrounded source terminal 16, 45 as will be explained.

Each trip-control relay 130, 130a comprises a normally attracted armature 136, 136a, carrying or comprising a movable switch element connected by conductors 73, 137 to said source 14, and a normally engaged contact 138, 138a normally constantly engaged by said movable element during normally closed circuit, when no trip magnet is operating, and disengaged during open circuit operation in the adjacent leg 5 or 7 of the trip loop. Said in-relay magnet of the trip receiver drops its armature 136a, whenever the adjacent leg 7 of the loop is shunted out by detector switches 47, 48, 51, 52, thereby (after 60 an interval longer than a water hammer impulse) to increase current flow in the trip circuit, by disabling a retarding means, now to be explained, for retarding the action of the trip loop current.

The retarding means

65

A retarding resistance 140 is interposed in the trip circuit 73, 133, 5, 6, 7, between the current source 16 and the control 12, whereby normally sufficient current for supervising the trip circuit 70 is allowed to pass, but not enough for operating the trip magnets 20, 20a; and said retarding means serves for shunting out said resistance when the detector is operated a time longer than the usual water hammer impulse. A retarding 75

relay 142, 143 has one end of its coil connected to a ground 145, and the other connected by conductors 146, 147, 148 and a normally closed switch 150, 151, with the normally engaged contact 138a of the tripper circuit in-relay 130a, whereby the retarding relay is normally energized, thereby attracting said retarding relay armature 142, and normally disconnecting from its contact 153, connected by conductor 154 to the conductor 133 between the resistance 140 and magnet 131. This holds the resistance 140 unshunted.

When the operation of detector switch 47, 48, 51, 52 short circuits the magnet 131a and drops the armature 136a, the circuit through conductors 15, 137, 136a, 138a, 148, 147, 146, magnet 143 and ground 145 is broken, and the magnet 143 would release its armature 142 immediately and short circuit the resistance 140, and thereby increase the strength of the trip loop current immediately, 20 were it not for retarding means now to be described.

This retarding means includes a double-throw switch 155, 156, 157 having one fixed contact 155 connected by conductor 146 to the ungrounded terminal of the retarding magnet 143. A condenser 159, having one plate grounded, has the other connected by a conductor 160 to the movable element 156 of said double-throw switch, whereby said condenser may be normally connected to said retarding magnet 143, whereby when said retarding relay magnet is energized, the condenser will be charged, and when the trip-circuit in-relay armature 136 drops and disconnects the retarding magnet from the source, 35 the condenser 159 discharges through the magnet 143 and holds the same energized a short time, thereby delaying the release of the armature 142 a few seconds, so as to prevent release by water hammer actuation of the detector 43, 44.

After the condenser has discharged, the armature 142 is released and engages said contact 153, thereby to shunt around said retarding resistance 140 and allow the passage of sufficient current for the operation by the trip magnet whose associated detector 43, 44 has been operated.

Interference-preventing means

An interference-preventing relay 164, 165 having its magnet coil 164 interposed in the conductor 77 of the transmitter circuit between the out-relay 70 and source 14, also has its armature 165 connected to the source, through conductors 77, 73. A contact 166 is engaged by the armature when normally attracted, and is connected by a conductor 167, 160, to the condenser 159, thereby during signaling to charge the condenser and energize the retarding magnet 143 during and between signal impulses, thereby deshunting said current-reducing resistance 140, thereby interposing the resistance and reducing the trip circuit current, thereby preventing other transmitted armatures from being raised to release with other transmitters.

Retard cut-out means

When the system is used where there is no water hammer, and where it is not desired that the initiation of transmission be retarded, the movable element 156 is moved from contact 155 to contact 157, thus preventing the charging of the condenser from the conductor 147.

It is still desirable, though, that the condenser discharge in a way to energize the magnet 143 to hold the resistance interposed during transmis-

sion, to prevent other transmitters from starting, as above explained.

To this end there is provided a retard cut-out relay 169, 170, having its armature 169 connected by conductor 73 to the current source, and one end of its magnet coil 170 connected to a ground 141, and the other connected to the fixed contact 157 of said double-throw switch, whereby when the movable element of the double-throw switch is on said last named fixed contact, said condenser will not discharge through the retarding relay magnet 143, thus allowing full current to pass to the trip circuit as soon as the trip-circuit in-relay armature falls thereby.

However, a contact 173, engaged by the armature of said cut-out relay when attracted is connected by conductor 146 to the ungrounded terminal of the retarding relay magnet coil 143, whereby during transmission the condenser 159 becomes charged from contact 166 and discharges through the cut-out relay magnet 170 to attract the cut-out relay armature 169, thereby to connect the retarding relay magnet 143 to the source and thereby break the shunt around the retarding resistance 140, thereby to weaken the trip circuit 25 current and prevent sufficient energization of a trip magnet of another transmitter for operation thereof, thus preventing mixing of the signals.

Trip-loop defect adjusting means

The relays 130, 130a constitute part of a control means for adjusting the supervisory trip control 12 for line defects. The trip-circuit relays respectively also include normally constantly disengaged contacts 190, 190a adapted to be engaged, when a detector is operated during normal closed circuit operation, and constantly engaged, when no transmitter is operated, during open circuit condition in the adjacent leg 5 or 7. A pilot lamp 194 for the trip receiver, having one ungrounded and one grounded terminal, is lighted from said relays by a control means for connecting said lamp to the proper contacts of said trip-relays to meet operating conditions for defects in the trip loop, as will now be explained. Said control means comprises an out-switch 198, and an in-switch 198a, and a ground switch 198g, each switch comprising a substantially semi-circular bank of contacts N, G, GO, O, OG, a rotatable shaft 199 and insulated contact arms 200, 200a, 200g, and an operating knob 201, as explained of switches 88, 88a, 88g. Conductors 202 connect the ungrounded terminal of said lamp to both contact arms 200, 200a; and a cam 203 on said shaft serves for opening said normally closed switch 150, 151, except during normal closed circuit operation.

Conductors 210 connect the operation contacts, N, G, GO of the out-switch 198 with the normally disengaged contact 190, allowing normal short pilot-lamp operation as by water hammer, and normal trip signal operation current (accompanied by code-signal current in the code signal receiver) through the out-relay when one of said contacts N, G, or GO is engaged by the 65 associated contact arm 200, and causing the supply to the pilot lamp of current of longer duration (unaccompanied by code-signals) should damage to the trip loop cause the armature 136 of the out-relay to come to rest on the normally disengaged contact 190 and to cause said pilot lamp to light up and indicate (when unaccompanied by code-signal) that the operator should advance the contact arms until the lamp is darkened.

Conductors 211 connect the open-circuit contact O and the grounded out-leg open-circuit contact OG of the switch 198 to the normally engaged contact 138, whereby when the condition of damage to the line requires the armature when idle to rest on the normally disengaged contact 190, indicator tripping indications may be received by the pilot lamp from the normally engaged contact, and whereby current of longer duration caused by change of such condition, will cause the in-relay armature 136 to rest on the normally engaged contact to cause the pilot lamp to light up for longer time to indicate (if unaccompanied by code-signals in the recorder) that the operator should move the contact arm 200 from the engaged bank contact and adjust the switch until the lamp becomes darkened.

Conductors 214 connect contacts N, G, OG of the switch 198a with the normally disengaged contact 190a, to cause the pilot lamp to light during indicator tripping if one of such contacts is engaged by a contact arm 200a, and to cause the supply to the pilot lamp of a current of longer duration (when unaccompanied by code-signal) to indicate that the arm should be revolved. Conductors 148, 215 connect contacts GO and O of the switch 198a to the normally engaged contact 138a, whereby when the condition of the line requires the armature to rest idle on the normally disengaged contact 190a, current indicating indicator tripping may be received by the lamp from the normally engaged contact 138a, and current of long duration, unaccompanied by code signal and caused by change of line location, will cause the pilot lamp to indicate that the contact arm should be moved from such bank contact.

A conductor 217 connects the in-magnet terminal 134 to the contact arm 200g of the ground switch; and a conductor 218 connects the normal operation contact N of the ground switch to a ground, for normal closed-circuit operation. Conductors 220 connect the remainder of the ground switch bank contacts G, GO, O, OG to the ungrounded terminal 16 of said current source, whereby when abnormal line loop condition requires that the current pass out through the in-magnet 131, the arm 200g will be shifted to one of contacts G, GO, O, OG, and the in-magnet will be connected thus by conductors 217, 220 to the current source.

Normal retarded trip loop operation

In normal idle condition, the transmitters and indicators are all as shown in Fig. 2 and at 18n of Fig. 1; and current passes through the trip loop 6, by way of terminal 16, conductor 73, resistance 146, conductors 133, magnets 131, leg 5, loop 6, all switches 47, 48, leg 7, magnet 131a, conductors 134, 217, arm 200g, conductor 218, to ground, thus supervising the trip loop and switches 47, 48, short circuiting the magnets 20, 20a through switches 47, 48, and holding raised the relay armature 136a, to cause current to find a path through terminal 16, conductors 73, 137, armature 136a, conductor 148, switch 150, 151, conductors 147, 146, magnet coil 143, and ground 145, thus holding the retard armature 142 away from the contact 153, thus maintaining the resistance 140 interposed in the supervised trip circuit.

As magnets 20, 20a are thus short-circuited and de-energized, the armature 34 is in lower position, and the transmitter is held against operation.

The transmitter loop 9 is also supervised, current passing through terminal 16, conductor 73, magnet 71, leg 8, loop 9, all switches 22, 23, 24, leg 10, magnet 71a, conductor 107, arm 90g, conductor 108, to ground 109.

An alarm will be initiated by flow in any pipe 45, and cause the fan 44 to rise. This will open switch 47, 48 (Fig. 2) and close the switch 51, 52, as at 18b (Fig. 1), directing current from the loop-part nearest the source through the magnet 20, switches 63, 62 and 52, 51, to ground 53, thus energizing magnet 20, but, because of the resistance 140 in the circuit, not sufficiently to attract the armature 34 (Fig. 2).

This operation short circuits the leg 1, through the ground 53, thus de-energizing magnet 131a, dropping relay armature 136a, disconnecting the magnet 143 from the armature 136a, and therefore from the current source.

Trip operation retarding

When said disconnecting takes place, the armature 142 is not released immediately because the condenser, which was charged, through conductors 160, 147, 148, will discharge through conductor 146 and magnet 143, thus holding the armature longer than a water hammer impulse.

If the detector movement was caused by water hammer, the switches 47, 48, 51, 52 will return to normal before the condenser completely discharges and releases the armature 142; but if the detector movement was caused by sprinkler-head operation, the detector switches will remain as at 18b until the condenser discharges, whereupon the armature 142 will be released, engaging contact 153, shunting current around resistance 140 through contact 153, thus allowing full current to pass through the magnet 20 and switch 51, 52, energizing the magnet 20 sufficiently to attract its armature and release the transmitter.

Whenever any detector switch, for instance of station 18a, is operated, current passes between grounds 53 and 15, thus short-circuiting out stations 18b, 18n, more remote from the source, so that their magnets cannot be energized to release the transmitter until the loop is restored to normal, as will be explained.

Normal transmission operation

The transmitter switches 22, 23, 24, are normally closed, and current normally passes from the main source 14 through magnets 71, the switches 22, 23, 24, magnets 71a, the conductor 107, the switch arms 90g, conductor 108, to ground, and then to the grounded terminal 15 of the battery 14. Thus the circuit is a closed supervised circuit. When the armature 34 (Fig. 2) is raised, the wheel 21 of that transmitter rotates and opens the switch 22, 23, 24, sending code signal in accordance with the teeth of that wheel. This intermittently breaks the circuit, intermittently closing the circuit through the source 14, conductors 73, 77, magnet 164, elements 76, 76a, conductors 100, 105, contacts N, arms 90, 90a, conductors 93, 94, to the recording receiver 85, and pilot lamp 84, respectively, to ground, thus recording the signal.

At this time the switch 95, 96 is open, for a purpose later to be explained. It will be noted that the wheel 21 is grounded but normally does not touch the spring pen member 24 of the switch 22, 23, 24.

During normal signal transmission, current passes between the signal wheel ground and 75.

ground 15, thus shorting-out the magnet 71a, allowing its armature to drop once for each tooth. At the same time the armature 76 is similarly dropped, but the leg 8 is not short circuited. Because of the capacity of the legs, and the fact that leg 10 is discharged and recharged, while the leg 8 is not, the armature 76a, in high speed work, lags somewhat, and gets out of step with the armature 76. This would cause impulses from one armature, say 76a, to reach the recorder 85 between the impulses from the other armature 76, thus rendering the record illegible. Therefore, the switch 98, 99 is provided to separate these currents during normal operation.

When the normal intermittent signal current is sent to the recorder through the contact N of switch 88, intermittent current also passes through contact N of switch 88a, thus flashing the lamp 84, but while the arms are on contacts N, the switch 95, 96 is open, and no current can pass from the lamp circuit to the recorder.

Under certain conditions, it might happen that the detector 43, 44 or other initiating means will, during a signal, restore to normal continuously, or one or more times. This would interrupt the signal; and such interruption is prevented by the land portion 40 (Fig. 2) of the cam 38, which moves under the bar 41, and holds the armature raised, releasing position, until the signal is completed and until the arbor is rewound to bring the recess 39 again under the bar.

Interference preventing

As soon as signaling commences, intermittent current passes through magnet coil 164, as above explained. This attracts armature 165, thus connecting the condenser, through conductors 160, 167, 73 to the source, thereby charging the condenser 159 and causing it to discharge through conductors 160, 156, 146, and magnet coil 143, thus attracting the armature 142 and interposing the resistance 140 in the trip circuit, thus preventing the passage, through the trip circuit, of current strong enough to operate any trip magnet, thus preventing the release of any other transmitter until after the signaling transmitter has finished its signal.

This prevents a second station from cutting in, whether it be nearer the source 14, or otherwise cut out or not.

Restoring the transmitter loop

As soon as the transmitter starts unwinding, the land portion 66 (Fig. 2) of the insulated cam 33, depresses the pen 65 of the switch member 60, thus closing the switch 60, 61 (as at 18a of Fig. 1) and short circuiting the magnets 20, 20a. This also opens the switch 62, 63 (as at 18a), thus entirely removing the ground 53, and closing the loop 6, ready for the next signal if, or as soon as, the resistance 140 is shunted out.

Successive operation

If, during transmission, several detectors be operated and be prevented from causing transmission, as first explained, the detector switch nearest the source 14 will short circuit (through grounds 53, 15) the more remote stations, so that as soon as transmission ceases and the line is restored, the nearest station will be the only one not short circuited, and will transmit, and then restore the line, to permit the next nearest station to transmit and restore the line, and so on until all of the stations progressively more remote from the source will successively operate.

When the transmitter runs down, the notch 64 will not quite have reached the pen 65, thus leaving the pen depressed, the ground switch 62, 63 open and the ground cut out, and leaving the switch 60, 61 closed, thus entirely cutting out the magnets 20, 20a until they are restored to the position shown, as explained above.

Adjusting for closed-circuit grounded transmitter loop

With the parts as shown in Fig. 1, suppose a ground as at 224G should occur. Current would pass direct from the ground 224G to the ground 15, thus short-circuiting the leg 10 and magnets 71a, deenergizing the magnet 71a, dropping the armature 76a, causing continuous current to pass from the source 14, through conductors 73, 77, armature 76a, conductors 104, arm 90a, conductor 94, pilot lamp 84, to ground, thus instructing the attendant to rotate the shaft 89 and revolve the arms 90 in clockwise direction until the arms come into contact with the contacts G of all of the bank switches. This operation also rotates the cam 98, 99 closing the switch 95, 96.

If when the elements 76, 76a, dropped to the contacts 80, 80a, the attendant had failed to rotate the shaft 89, the pilot lamp would have remained lighted, calling attention to the failure of the operator.

Closed-circuit grounded transmitter-loop operation

As soon as the arms have been as above noted moved to contacts G, current may pass from the source, through conductors 73, 110, contact G 35 of switch 88g, arm 90g, conductor 107, magnet 71a, leg 10, to the ground 224G, thus raising armature 76a. At the same time current passes from source 14, through the magnet 70 and leg 8, to ground 224G, thus raising armature 76. 40

Now if a wheel 21 on either side of the ground 224G be rotated in sending the signal, the circuit through the adjacent leg 8 or 10 and magnet 71 or 71a will be broken, the armature 76 or 76a will be intermittently dropped, and signal current 45 will pass intermittently through conductors 100 or 104, arm 90 or 90a, conductor 93, or conductors 94, 97, switch 95, 96, conductor 93, to the recorder 85, and a signal will be recorded at the recorder.

If the signal is sent from the signal box 18 to the left of the ground 224G, the left hand magnet 71 will be operated, and vice versa.

Restoring apparatus after transmitter loop repair

While the arms 90 are thus resting on contacts 55 G, repair men should be sent to repair the line. As soon as the loop is restored to normal, no current will pass, since both ends of the loop are still connected to the terminal 16, and there is no connection with the ground 109. This will cause 60 the dropping of both armatures 76, 76a, so that continuous current will pass through conductors 100 and 104, said arms and pilot lamp in any abnormal position of the arms indicating to the attendant to revolve the arms forwardly from 65 these positions until the arms again engage the normal contacts N.

The operation of restoring the apparatus from any line position to normal, after repair, is included in the preceding paragraph, and need not 70 be repeated hereinafter.

Ground-open transmitter-loop operation

Should it happen that the circuit operating as shown in Fig. 1 should develop both a ground 75

224G and an open 225, the right hand magnet 71a would be deenergized, the right hand armature 76a would drop. This would cause continuous current to find a path through conductors 73, 77, 104, arms 90, conductor 94, and pilot lamp, indicating that the attendant should move the arm from contacts N at least to contact G; but contact G of switch 88a is charged by conductor 104, from the dropped armature, thus lighting the pilot lamp, causing the attendant to revolve the arm to contact GO.

In this position, a closed circuit is formed through the leg 8 and ground 224G, so that the armature 76 remains raised, preventing the passage of current therefrom to conductor 100 and the pilot lamp and recorder; but if a station 18a or 18b, to the left of the ground-open 224G, 225, be operated, the leg 8 will be intermittently broken, the armature 76 will be intermittently dropped, and intermittent current will pass through conductors 100, 93, and the recorder will operate.

In this condition, no current can pass the magnets 71a because of the open 225. This causes the armature 76a to drop away from contact 78a, thus preventing current from armature 76a from reaching the pilot lamp, thus indicating that the attendant should allow the arms to remain on contacts GO. But the leg 10 is charged; and when a station 18n is operated current passes through conductor 110, arm 90g, conductors 107 and 10, and the ground of station 18n, thus intermittently raising the armature 76a, sending intermittent current through conductor 105, arm 88a, conductors 97, 93, and the recorder.

Open-transmitter-loop operation

If when the parts are as in Fig. 1, there should occur an accidental break in the line as at 225, the circuit through the loop 8, 9, 10, would be broken, magnets 71 and 71a would be deenergized, armatures 76 and 76a would drop, close the circuit through conductor 104, and arm 90a, and light up the pilot lamp, warning the attendant to move the switch arms from the position N, at least as far as the intermediate contacts G and GO. As no current can pass the open, and therefore the magnets 71, 71a, the armatures must stay down, and current must pass through conductors 100 and 104, and at least through one arm 90 or 90a, until contact O is reached, whereupon the lamp would darken, as neither contact O is connected to an upper contact 78 or 78a.

In this position, the leg 8 is still connected to the main source; and the leg 10 is connected through magnet 71a, conductor 107, arm 90g, conductors 110, 73, to the source. Thus both legs and both sides of the open 41 will be charged, and if either transmitter 18a or 18b, or 18n is operated, current would pass from the source, through one of the magnets 71 or 71a, to a switch 22, 23, 24. The tooth of the wheel 21 touches the switch member 24 before it opens the switch, and current would pass through the toothed wheel 21, the ground of the station, the ground 15, to the source 14. This would cause the armatures 76, 76a, to intermittently rise, and the signal current would pass through conductors 101 or 105, arms 90 or 90a, and thence to the recorder. Thus it is seen that the circuit could operate even with an open, as at 225.

Open-grounded transmitter-loop operation

Suppose the parts are as is Fig. 1, and a break 75 225 and a ground 226G should develop. When

this happens, no current can pass through the open 225 to the magnet 71a, and the armature 76 and 76a would drop from the position of Fig. 1 into contact with the contact 80a, thus causing continuous current to pass through conductor 104, 5 arm 90a, and conductor 94, to pilot lamp. This will cause the attendant to move the bank switch arms across successive contacts G, GO and O; but at any of these positions there is always at least one contact connected to a lower contact 80 10 or 80a; and the attendant would at last move the arms to contacts OG.

In this position with the arms on contacts OG, the armature 76 is down, because no current passes the open 225; but the armature 76a is 15 up, because current passes through conductors 110, arm 90a, conductor 107, magnet 71a, leg 10, and ground 226G. Then if a signal be sent from station 18a, current passes through the magnet 71, leg 8, and the ground of station 18a, thus 20 intermittently raising the armature 76, sending current through conductors 101, contact OG, arm 90, conductor 93, to the recorder. If station 18n be operated, the circuit in leg 10 is thereby broken, armature 76a intermittently 25 drops, and intermittent current passes through conductors 104, arm 90a, conductors 97, 93 and the recorder.

Adjusting from one to another abnormal transmitter-loop condition

Should the apparatus be set for any abnormal condition, such as a grounded closed circuit, and then the line condition change to a condition corresponding to any subsequent switch arm position in a clockwise direction, such as an open-ground position, the switch arms would obviously be moved forward from the first abnormal position to the subsequent position, just as if the first abnormal condition had not existed. Thus 40 this operation requires no further explanation.

If, however, an abnormal condition such as open-ground, having a later switch position, as at the contact OG, should become changed to a condition corresponding to a preceding switch 45 position, such as the position at contacts G, GO or O, the apparatus would take care of this operation also.

Suppose, for instance, that there be the open-ground condition, with the circuit broken at 50 225 and grounded at 226G, switch arms on contacts OG, and the armature 76 down, and the armature 76a up. Then if the break 225 should close, and there be left only the ground, current would pass through the magnet 71, the armature 55 76 would rise, and current would pass through conductor 101, contact OG, arm 90, conductors 93, 97, 94 to the pilot lamp, and the attendant would move the arm forwardly.

For every operating position, the arms 90, 90a 60 are connected to one uncharged associated relay contact, and every line change changes the position of at least one armature, charging a previously uncharged relay contact, causing the pilot lamp to light until the arms are moved around 65 to their proper position.

In every operating position as above described, no current passes the conductor 77 and magnet coil 164 except during signaling.

Adjustments for trip-loop defects

Normal retarded trip-loop operation was described above. The trip-loop is also subject to line defect in a manner similar to that of the transmitter loop, entirely independently of the 75

transmitter loop, as either or both loops may have similar or different defects, or no defect, at the same time. Adjustments for defects in the different loops are entirely independent.

In all abnormal trip loop adjustments the switch 150, 151 is opened by a cam 203, thus deenergizing magnet 143 and cutting out the retarding resistance 140; but in all cases the trip loop will operate to send signals until proper repairs are made.

Adjustment for closed-circuit grounded trip loop

With the parts as shown in Fig. 1, suppose a ground as at 229G should occur. Current would 15 pass direct from the ground 229G to the ground 15, thus short-circuiting the line leg 7 and magnets 131a, deenergizing the magnet 131a, dropping the armature 136a, causing continuous current to pass from the source 16, through conductors 73, 131, armature 136a, conductor 214, contact N, arm 200a, conductor 202, through pilot lamp 194, to ground, thus lighting the pilot lamp. If this is unaccompanied by code signal, the attendant rotates the knob 201 until the arms 25 come into contact with contacts G of all the switches 198, 198a, 198g, thus also opening the switch 150, 151 by the action of the cam 203. If the pilot lamp 194 lights up for only a short time and is followed by code signal at the recorder 85, the attendant knows that the shaft 199 and the switch arms should not be adjusted.

Closed-circuit grounded trip-loop operation

As soon as the arms have been as above noted 35 moved to contacts G, current may pass from the source 14, through conductors 73, 220, contact G of switch 198g, arm 200g, conductor 217, magnet 131a, leg 7, to ground 229G, thus raising armature 136a. At the same time, since the switch 150, 151 is open, and armature 142 released, current passes from source 14, through conductors 73, 144, armature 142, conductors 154, 133, magnet 131, leg 5, to ground 229G, thus supervising both legs 5 and 7, raising armature 136, and darkening the lamp, since both armatures 136, 136a have been raised.

Now if a detector 43, 44 on either side of the ground 229G, be actuated, a magnet 20 or 20a 50 will be energized and release the transmitter as in normal operation.

If the signal is sent from the signal box 18a or 18b to the left of the ground 229G, the left hand magnet 20 will be energized, and vice versa.

After the repair man removes the ground 229G, no current will pass, since both ends of the loop are connected to the terminal 16, and the bank switches 198, 198a, 198b will be restored to normal, as described of the transmitter loop.

The operation of restoring the control apparatus 12 from any position to normal after repair, will be understood from the preceding descriptions, and need not be repeated.

Ground-open trip-loop operation

Should it happen that the circuit operating as shown in Fig. 1 should develop both a ground 229G and an open 230, the right hand magnet 70 131a would be deenergized, and the right hand armature 136a would drop. This would cause continuous current (unaccompanied by code-signal) to find a path through conductors 73, 137, 214, arm 200a, conductors 202, causing the 75 lamp 194 to light up, indicating to the attendant

to rotate the arm 200a to contact GO. During this movement the arm 200g passes the contact G of switch 198g, and reaches contact GO, and in both cases the magnet 131a is connected to the main source through conductor 217, arm 200g, and conductors 220, 73; but no current passes because of the open at 230, and the armature 136a remains lowered.

In this position, a closed circuit is formed through the leg 5 and ground 229G; and if a 10 detector of station 18a or 18b, to the left of the ground-open 229G, 230, be operated, current will pass through the magnet 20, and attract and release the transmitter. At the same time, the tripping current will merely pass between the 15 ground 53 of the detector switch and the ground 15, so there will be no change at the armature 136. As the open exists at 230 there will be no change at the armature 136a.

In this condition, no current can pass the magnets 131a because of the open 230, but the leg 7 is charged; and when the detector of a station 18n is operated current passes through the magnet 20a, and the ground 53 of that station, thus raising the armature 34 and releasing the trans- 25 mittor.

When this takes place, current will pass through magnet 131a, and lamp 194; but as this will be accompanied by code signal at the recorder 85, the attendant will not adjust the arms 200a, 200b. 30

Adjustments for other trip-loop defects

From the above, it is seen that the tripping magnets 20, 20a may be operated from either leg 5 or 7 when the leg is either charged or 35 uncharged, and that these adjustments for trip loop defects caused by any combination of grounds 229G or 231G and open 230, are similar to corresponding adjustments for transmitter loop defects, and need not be further described. 40

Retard-cut-out operation

Any abnormal position of switches 198, 198a opens the switch 150, 151 and cuts out the retarding resistance 140 so that any magnet 20, 20a 45 may be actuated; but repair men are sent out as soon as possible.

The operation with the retarding resistance 140 cut-out allows the trip magnets to operate as soon as the signal initiating means 43 (Fig. 2) 50 is operated.

The apparatus is also adjusted to cut-out this trip-retard (when the retarding effect is not needed) by moving the switch element 156 (Fig. 1) 55 to engage the fixed element 157. This operation will be understood by reading the description of the retard cut-out means as given hereinbefore.

But in any case, operation of a transmitter and relay 164 causes the resistance 140 to be inter- 60 posed.

The invention claimed is:

1. In combination, a closed circuit including a trip loop; transmitters through which the loop passes, each including a trip magnet adapted to release the transmitter from normal rest positions when sufficiently energized; signal initiating means for each transmitter for directing current from the trip-loop through the trip magnet of such transmitter; and retarded means operated by the trip circuit during signal initiating for 70 increasing the current in the trip circuit after a delay after the current is directed through the trip magnet.

2. In combination, a closed circuit including a trip loop; transmitters through which the loop 75

passes, each including a trip magnet adapted to release the transmitter when sufficiently energized; signal initiating means, subject to water hammer, for each transmitter for directing current from the trip loop through the trip magnet of such transmitter; a reducing means associated with the circuit for reducing the current in the trip circuit, to prevent release of the transmitter; and retarded means operated by the trip circuit during signal initiating for disabling the reducing means after a delay after the current is directed through the trip magnet, said delay being long enough to avoid water hammer operation.

3. In combination, a closed circuit including a trip loop; transmitters through which the loop passes, each including a trip magnet adapted to release the transmitter when sufficiently energized; signal initiating means for each transmitter for directing current from the trip loop through the trip magnet of such transmitter; a resistance interposed in the circuit, for reducing the current in the trip circuit, to prevent release of the transmitter; and retarded means operated by the trip circuit during signal initiating for removing the resistance, after a delay after the current is directed through the trip magnet for increasing the current in the trip circuit sufficient for releasing operation.

4. A system comprising a trip circuit; a transmitter, including a trip magnet adapted to release the transmitter when sufficiently energized; signal initiating means constructed and connected for directing current from the trip-circuit through the trip magnet and to short-circuit part of the trip circuit; reducing resistance in the trip-circuit, for preventing the action of the trip magnets; a retarding relay means, tending to shunt out said resistance, and actuated by said trip circuit, for preventing the shunting-out until the trip circuit is short-circuited; a condenser charged from said trip circuit and discharging through the magnet coil of said relay; a non-interference means operated by the transmitter during signaling, for charging said condenser.

45 5. A system comprising a trip circuit; a transmitter circuit; transmitters in said circuits each including a trip magnet adapted to release the transmitter when sufficiently energized; initiating means for directing current from the trip-circuit through the trip magnet; a resistance in the trip-circuit, for preventing the action of the trip magnets; a retarding relay means, including means for shunting out said resistance, and controlled by said trip circuit, for preventing the shunting out said resistance; a condenser charged from said trip circuit, and discharging through the magnet coil of said relay.

6. In combination, a line comprising transmitters adapted for McCulloh operation; a signal receiver including a grounded source connected to the out-leg of said line, and an "out" relay and "in" relay in the out-leg and in-leg respectively; each relay comprising an armature connected to the source, a normally engaged contact normally engageable by said armature, and a normally disengaged contact; control means including an in-switch and an out-switch for said relays respectively, each switch including a movable arm and contacts for connecting said arms to the proper contacts of said relays, to meet operating conditions for defects in the transmitter loop; a recorder connected to the arms of the switches and means for disconnecting the in-switch arm from the recorder during normal operation.

7. In combination, a signal receiver, including a current source having a grounded and an ungrounded terminal; a line connected to the ungrounded terminal and comprising transmitters, each including a grounded signal wheel, a normally closed switch in the transmitter loop normally out of contact with the wheel; means to release the transmitter; said signal receiver including an "out" relay and "in" relay in the out-leg and in-leg respectively; each relay comprising an armature connected to the source, a normally engaged contact normally engageable by said armature and a normally disengaged contact; control means including an in-switch for the in-relay and out-switch for each relay, the out-switch including a movable arm and contacts for connecting said arms to the proper contacts of said relays to meet operating conditions for defects in the transmitter loop; a recorder and a pilot lamp connected to the arms of the out-switch and in-switch respectively; said control means connecting the in-relay magnet to the ground during closed-circuit normal operation, and to the ungrounded terminal during abnormal operation; and means controlled by the control means for electrically connecting said arms in any operative condition except during normal operation.

8. In combination, a current source having a grounded and ungrounded terminal, a trip loop connected to the ungrounded terminal of the source; transmitters, each transmitter including a pair of trip magnets in the trip loop, an armature adapted to be attracted by either magnet to release the transmitter; a detector comprising means for directing current from said source through one magnet to the ground to operate the transmitter; a supervisory trip-control, including, in the trip-loop, an "in"-relay, comprising a normally attracted trip-armature connected to said source, and a normally engaged contact engageable by said armature; retarding means in the trip-circuit for preventing the action of the trip magnets, and controlled by said trip armature, for preventing the retarding means from retarding unless the detector is operated longer than a predetermined length of time; control means for adjusting the loop and trip receiver in accordance with defects in the trip loop; and means operated by the control means when adjusted to abnormal operation, for preventing the retarding means from preventing trip-magnet action.

9. In combination, a current source having a grounded and an ungrounded terminal; a trip loop connected to the ungrounded terminal; transmitters in the trip loop, each set in operation with current from either direction; a detector comprising means for directing current from said loop through the transmitter to a ground to operate the transmitter; a trip-control including, in the trip loop, an "in"-relay; retarding means in the trip circuit for preventing the action of the transmitters, and controlled by said relay; control means for connecting the loop in-leg to a ground or the ungrounded terminal and adjusting the trip control, in accordance with defects in the trip loop; and means for disconnecting the retarding means during abnormal operation.

10. In combination, a current source having a grounded and an ungrounded terminal; a trip loop connected to the ungrounded terminal; transmitters in the trip loop, each operated with current from either direction; a detector, com-

prising means for directing current from said loop through the transmitter to a ground, to operate the transmitter; a trip-control, including, in the trip loop, an "in"-relay, comprising a normally attracted trip-armature connected to said source, and a normally engaged contact engageable by said armature; retarding means in the trip-circuit for preventing the action of the transmitters and controlled current from said contact; control means for adjusting the trip control in accordance with defects in the trip loop, and connecting the in-leg of the loop to the ground during normal operation, and to the ungrounded terminal during abnormal operation; and means operated by the control means for disconnecting the retarding means from said contact during abnormal operation.

11. In combination, a grounded current source; code-signal-impulse transmitters each having a ground; a trip-loop passing through the transmitters and having one end connected to said source and the other end grounded; means separate from the trip loop for transmitting code signals from the transmitters; each transmitter including a trip magnet in the trip loop, and an armature adapted to be attracted by the magnet to start the transmitter; a signal initiating means for each transmitter normally shunting the magnet and adapted to break the shunt and direct current from the trip loop through one magnet to the transmitter ground to start the transmitter and short circuit the trip magnets of more remote transmitters to prevent the more remote transmitters from initiating signals while the less remote transmitters are transmitting; means actuated by the transmitter at the beginning of transmission for removing its ground and short circuiting its trip magnets during and after transmission and after the transmitter comes to rest.

12. In combination, a grounded current source; code-signal-impulse transmitters each having a ground; a trip-loop passing through the transmitters and having one end connected to said source and the other end grounded; means separate from the trip loop for transmitting code signals from the transmitters; each transmitter including a pair of trip magnets in the trip loop, and an armature adapted to be attracted by either magnet to start the transmitter; a signal initiating means for each transmitter normally shunting the magnets and adapted to break the shunt and direct current from the trip loop through one magnet to the transmitter ground to start the transmitter and thereby short-circuit the trip magnets of more remote transmitters; means actuated by the transmitter at the beginning of transmission for removing its ground, and short circuiting its trip magnets, during and after transmission; and control means to disconnect said outer end from the ground and connect it to the ungrounded terminal of the source.

13. In combination, a trip loop; a single grounded current source therefor; code-signal-impulse transmitters each having a ground; said trip-loop passing through the transmitters and having one end connected to said source and the other end grounded; means separate from the trip loop for transmitting code signals from the transmitters; each transmitter including a trip magnet in the trip loop, and an armature adapted to be attracted by the magnet to start the transmitter; a signal initiating means for each transmitter adapted when in normal position for nor-

mally shunting the magnet and adapted when in actuated position to break the shunt and direct current from the trip loop through the magnet to the transmitter ground to start the transmitter and thereby short circuit the trip magnets or more remote transmitters; means actuated by the transmitter at the beginning of transmission and functioning in either position of the initiating means for removing its ground and directly short circuiting its trip magnets, during and after transmission, to prepare the trip loop for waiting stations; means for compelling a transmitting station to complete its code; and means for preventing trip loop current from starting other transmitter while a station is operating.

14. In combination, a source of current; a trip loop connected thereto; transmitters, each including a trip magnet adapted when sufficiently energized to cause the transmitter to operate from normal rest position; signal initiating means for shorting out the trip magnets of more remote transmitters and for causing current from the trip loop to pass through the trip magnet before the transmitter has started, thereby to start the transmitter; and means operated by the transmitter during transmitting, for reducing the current in the trip circuit to prevent release of another transmitter.

15. In combination, a grounded source of current; a transmitter circuit and a trip circuit each having one end grounded and the other connected to said source; means for disconnecting such grounds and connecting both ends of each circuit to said source; transmitters, each including a normally closed code switch, means for grounding the code switch, a pair of trip magnets disposed in series in the trip circuit, a ground connected to the connection between the magnets, either magnet being adapted when sufficiently energized to cause the transmitter to operate; signal initiating means for causing current from the trip circuit to pass through either trip magnet to ground, thereby to start the transmitter; means set in operation by the transmitter during transmitting, for reducing the current in the trip circuit enough to prevent release of another transmitter; and code signal receiving means operable by current in either end of the transmitter circuit.

16. In combination, a grounded source of current; a transmitter circuit and a trip circuit each having one end grounded and the other connected to said source; means for disconnecting such grounds and connecting both ends of each circuit to said source; transmitters, each including a pair of trip magnets in series in the trip circuit, a ground connected to the connection between the magnets, either magnet being adapted when sufficiently energized to cause the transmitter to operate from normal rest position; and signal initiating means for causing current from the trip circuit to pass through either trip magnet to ground before the transmitter has started, thereby to start the transmitter and short out more remote trip magnets.

17. In combination, a grounded current source; code-signal-impulse transmitters each having a ground; a trip-loop passing through the transmitters and having one end connected to said source and the other end grounded; means separate from the trip loop for transmitting code signals from the transmitters; each transmitter including a trip magnet in the trip loop, and an armature adapted to be attracted by the magnet, when sufficiently energized, to start the trans-

mitter; a control magnet in the trip loop between said ground and the transmitters; a signal initiating means for each transmitter adapted to direct current from the trip loop through the magnet to the transmitter ground to partially energize the trip magnet and to short circuit the control

magnet; means set in operation by the deenergization of the control magnet for increasing the current in the trip circuit, to sufficiently energize the partially energized trip magnet to start the transmitter.
